ELECTRODYNAMIC COMPRESSOR

Emmett F. Sarver, Hays, Kans., assignor to General Motors Corporation, Dayton, Ohio, a corporation of Delaware

Application November 8, 1937, Serial No. 173,389

3 Claims. (Cl. 230—55)

This invention relates to compressors and particularly to those for compressing gaseous fluids such as used in refrigeration systems and the like.

The principal objects of the invention are to provide an electrodynamic compressor that is of simple and inexpensive construction; to provide a compressor of this character which does not require lubrication; to provide a compressor that is compact and adapted to be completely sealed in a gas-tight housing; to provide a compressor that is quiet in operation; and to provide a compressor that will function successfully though the voltage of the current supply fluctuates widely.

In accomplishing these and other objects of the invention, as hereinafter pointed out, I have provided improved details of structure, the preferred form of which is illustrated in the accompanying drawings, wherein:

Fig. 1 is a longitudinal section through an electrodynamic compressor constructed in accordance with the present invention.

Fig. 2 is a cross-section through the compressor on the line 2—2 of Fig. 1.

Fig. 3 is a cross-section on the line 3—3 of Fig. 1.

Fig. 4 is a cross-section through one of the bellows on the line 4—4 of Fig. 1.

Referring more in detail to the drawings:

1 designates a compressor constructed in accordance with the present invention and which includes a gas-tight casing or shell 2, comprising mated sections 3 and 4 and an interposed spacer ring 5. The sections include cylindrical walls 6 closed at one of their ends by heads 7 and provided at their opposite ends with radially extending peripheral flanges 8. The ring 5 conforms to the inner diameter of the sections and its outer diameter corresponds to the outer diameter of the flanges 8. The ring 5 is provided with a radially extending outlet port 9, having connection with a discharge duct 10.

Engaged between the flanges 8 and the ring 5 are compressor heads 11 and 12, each including a circular disk having cylindrical offsets located in the axis of the casing and extending in the direction of the heads 7. The inner ends of the offsets are open and communicate directly with the space 13 afforded by the thickness of the spacer ring. The outer ends of the offsets are closed by integral heads 14 and 15, having axial ports 16 and 17 that are closed on the inner sides of the heads by check valves 18 and 19. The check valves are of reed-like construction and

preferably formed of extremely light weight, flexible, metallic strips 20 that have one end overlying the ports and their opposite ends secured to the heads 14 and 15 by fastening devices, such as screws 21, whereby the free ends are adapted to flex to and from covering relation with the ports responsive to movement of gaseous fluid therethrough, as later described. The light weight construction of the check valves is important for the reason that they must have very low inertia, and so that they can open and close quickly responsive to pulsations produced by an alternating current as later described.

The compressor heads carry flexible metallic bellows 22 and 23 that are of cylindrical character and arranged in coaxial sleeved relation with the offset portions of the compressor heads. The bellows 22 and 23 include a plurality of accordion folds 24, and have their inner ends 25 welded or otherwise attached to the outer faces of the compressor heads, as indicated at 26. The opposite ends of the bellows terminate in laterally extending peripheral flanges 27 which are welded or otherwise secured to the peripheries of diaphragm plates 28 and 29, which close the outer ends of the respective bellows and cooperate with the compressor heads to form compression chambers 30 and 31. The diaphragms 28 and 29 are provided with axial ports 32 and 33 that are normally closed on the inner sides of the diaphragms by check valves 34 and 35 of the same light weight, flexible construction as the check valves previously described.

The bellows diaphragms are pulsated back and forth in the manner of pistons to draw gaseous fluid through the ports 32 and 33 and to compress the fluid through the ports 16 and 17 upon contraction of the bellows by electrodynamic motors 36 and 37.

The motors 36 and 37 are housed within the outer ends of the respective casing sections. Each motor includes a magnetizable, ring-like body 38, closely conforming to the inner diameter of the shell sections and which abuts against the inner faces of the respective heads 7. The rings are preferably secured in position by pins 39 extending through suitable openings 40 in the cylindrical walls of the sections and into aligning sockets 41 in the peripheries of the rings. The rings are provided with cylindrical recesses 42 on their inner sides to accommodate field coil windings 43 for the motor 36, and 44 for the motor 37. Extending through the center of the field windings are cylindrical pole pieces 45 and 46, having reduced ends 47 engaged in axial

openings 48 of the rings 38 and which are staked therein as indicated at 49. The opposite ends of the pole pieces project from the coils in the directions of the diaphragms 28 and 29. The open sides of the recesses 42 are closed by ring-like disks 50 that are sleeved over the projecting ends of the pole pieces. Secured to the inner faces of the rings 38 are substantially heavy magnetizable rings 51 that conform in outer diameter therewith and have central, cylindrical openings of larger diameters than the pole pieces to form annular fields or gaps 52 therebetween. The rings 51 are secured to the ring-like bodies 38, so as to retain the field windings, by fastening devices, such as screws 53, that extend through openings 54 in the ring 51 and into threaded sockets 55 in the rings 38.

Fixed to the outer face of each diaphragm plate, and operable over the pole pieces, are armature coils 56 and 57 that are contained between cylindrical sleeves 58 and 59, the inner sleeve being of suitable diameter to move freely over the pole pieces and the outer sleeves to move freely within the rings 51. The ends of the sleeves are closed by rings 60 and 61 to retain the coil windings therebetween. The sleeves and rings thus described are formed of non-magnetic, and non-conductive materials. The inner ends of the outer sleeves are engaged within annular rings 62 having flanges 63 that are riveted or otherwise attached to the outer faces of the diaphragm plates, as indicated at 64. The sleeves are also riveted or otherwise secured to the retaining rings so that they are carried with the diaphragm plates to effect movement thereof as later described. The inner ends of the sleeves and rings are provided with radially extending ports 65, through which gaseous fluid is delivered for flow through the ports 38 and 33 into the compression chambers of the bellows.

The terminal ends 66 and 67 for the field coil 43, and 68 and 69 for the field coil 44, extend through channels 70 in the respective rings 50 and connect with binding posts 71-72 and 73-74 that are insulatingly supported in the outer walls of the casing sections, as clearly shown in Fig. 1. The terminal ends 75 and 76 of the moving coil 56, and 77 and 78 for the moving coil 57, are connected by flexible leads 79 with similar binding posts 80-81 and 82-83 respectively.

When the motor and bellows units thus described are installed in their respective casing sections, the sections are secured to the compressor heads and to the respective sides of the ring 5 by fastening devices, such as bolts 84, extending through aligning openings 85 in the flanges 8, 86 in the compressor heads, and 87 in the ring 5, as shown in Fig. 1. The spaces surrounding the bellows form inlet chambers 88 and 89 that are supplied with gaseous medium through ducts 90 and 91, leading from a source of supply such as a refrigerating system (not shown). The binding posts 72 and 74 are connected in series by a conductor 92, while the corresponding binding posts 71-72 are connected by conductors 93 and 94 with a source of direct current supply, for example, with the filament and plate leads of a full wave rectifier 95, which rectifies an alternating current supplied through the secondary windings 96 and 97 of a transformer 98, the windings being arranged so that the pole pieces of the respective motors have reverse polarity. The binding posts 81 and 83 of the movable coils are connected by a common conductor 99 and the binding posts 80 and 82 are connected by conductors

100 and 101 with a secondary winding 102 of the transformer. The primary 103 of the transformer is supplied with a suitable alternating current through the service lines 104 and 105 under control of a switch 106.

With the construction illustrated and described, the rings 38 and 50, including the pole pieces, become strongly magnetized, and due to the connecting of the field windings, one pole piece presents a north pole and the other a south pole, while the rings 51 are of the opposite poles so that a strong, magnetic field is built up across the annular gaps in which the movable coils are located, the movable coils being supplied with alternating current forming electromagnets of changing polarity to set up alternating magnetic fields within the constant magnetic fields surrounding the pole pieces. With this arrangement the poles of the coils reverse in accordance with the alternations of the current so that the coils are alternately repulsed and attracted by the pole pieces, setting up a reciprocating movement of the bellows. The winding of the movable coils is such that they move toward each other at the same time causing equal and opposite reactions on the bellows, thereby preventing vibration incidental to the reciprocatory movement. As the diaphragms are drawn outwardly from the compressor heads to expand the respective bellows, gaseous fluid supplied through the ducts 90 and 91 is passed through the ports 32 and 33 and into the interior of the bellows, the increasing pressure in the intake lifting the reed-like check valves 34 and 35. During this movement of the bellows the check valves 18 and 19 are closed. When the current flow is reversed, the polarity of the coils change and they are repulsed to move the diaphragms inwardly toward the compressor heads, trapping the gaseous fluid within the bellows chamber and forcing it through the ports 16 and 17 and past the reed-like check valves 18 and 19 into the space 13 for discharge under higher pressure through the outlet duct 10, thus completing one cycle of operation. It is obvious that a cycle occurs on each alternation of the current flow in the movable coils, so that the bellows continue to pump the gaseous fluid from the ducts 90 and 91 and discharge it under higher pressure through the duct 10 for return to the refrigerating system.

From the foregoing it is obvious that I have provided an electrodynamic compressor that is of simple and inexpensive construction and which may be sealed within a gas-tight case, as shown. It is also obvious that since there are no parts moving in sliding contact there is no necessity for lubrication and no parts subject to frictional wear. The compressor is also of sturdy construction and not likely to get out of order due to the simplicity and few working parts.

What I claim and desire to secure by Letters Patent is:

1. In a device of the character described, walls forming a chamber, a pair of opposed fluid displacing members carried by the walls and discharging into said chamber, a dynamic coil for each displacing member, a non-magnetic support connecting the respective dynamic coils with their displacing members, magnets for establishing magnetic fields in the zone of said dynamic coils, and means simultaneously supplying to said coils an alternating electrical current at commercial frequencies to effect synchronous movement of the coils to pulsate the displacing members.
2. In an apparatus of the character described,

a casing, a pair of spaced heads in the casing having outwardly offset portions provided with discharge ports, bellows respectively connected with the spaced heads in telescoping relation with said offset portions to form compression chambers, diaphragm heads closing the opposite ends of the bellows and having inlet ports into the compression chambers, valves controlling said inlet and outlet ports, means supplying a gaseous fluid to the casing, means for conducting the gaseous fluid from the space between said spaced heads, a dynamic coil for each bellows, a non-magnetic support on each diaphragm head for mounting the respective dynamic coils, means in the casing for establishing individual magnetic fields in the zone of the respective dynamic coils, and means for supplying a fluctuating current to the coils for establishing an alternating polarity in said coils relatively to the magnetic fields for effecting expansion and contraction of the bellows responsive to dynamic movement of the coils in the magnetic fields.

3. In an apparatus of the character described, a casing, a pair of spaced heads in the casing

having outwardly offset portions provided with discharge ports, bellows respectively connected with the spaced heads in telescoping relation with said offset portions to form compression chambers, diaphragm heads closing the opposite ends of the bellows and having inlet ports into the compression chambers, valves controlling said inlet and outlet ports, means supplying a gaseous fluid to the casing, means for conducting the gaseous fluid from the space between said spaced heads, a dynamic coil for each bellows, a non-magnetic support on each diaphragm head for mounting the respective dynamic coils, electromagnets in the casing for establishing individual magnetic fields in the zone of the respective dynamic coils, means for supplying a fluctuating current to the coils for establishing an alternating polarity in said coils relatively to the magnetic fields for effecting expansion and contraction of the bellows responsive to dynamic movement of the coils in the magnetic fields, and means supplying a direct current to the electromagnets.
